(57) **CLAIM**

The ornamental design for a warehouse robot, as shown and described.

DESCRIPTION

FIG. 1 is a first perspective view of a warehouse robot;
FIG. 2 is a second perspective view thereof;
FIG. 3 is a front view thereof;
FIG. 4 is a rear view thereof;
FIG. 5 is a left view thereof;
FIG. 6 is a right view thereof;
FIG. 7 is a top view thereof;
FIG. 8 is a bottom view thereof;
FIG. 9 is an enlarged detailed view taken from line 9 in FIG. 1;
FIG. 10 is an enlarged detail view taken from line 10 in FIG. 1;
FIG. 11 is an enlarged detail view taken from line 11 in FIG. 2;
FIG. 12 is an enlarged detail view taken from line 12 in FIG. 3;
FIG. 13 is an enlarged detail view taken from line 13 in FIG. 3;
FIG. 14 is an enlarged detail view taken from line 14 in FIG. 3;
FIG. 15 is an enlarged detail view taken from line 15 in FIG. 4;
FIG. 16 is an enlarged detail view taken from line 16 in FIG. 4;
FIG. 17 is an enlarged detail view taken from line 17 in FIG. 4;
FIG. 18 is an enlarged detail view taken from line 18 in FIG. 4;
FIG. 19 is an enlarged detail view taken from line 19 in FIG. 5;

(Continued)

FIG. 20 is an enlarged detail view taken from line 20 in FIG. 5;

FIG. 21 is an enlarged detail view taken from line 21 in FIG. 5;

FIG. 22 is an enlarged detail view taken from line 22 in FIG. 5;

FIG. 23 is an enlarged detail view taken from line 23 in FIG. 6;

FIG. 24 is an enlarged detail view taken from line 24 in FIG. 6;

FIG. 25 is an enlarged detail view taken from line 25 in FIG. 6; and,

FIG. 26 is an enlarged detail view taken from line 23 in FIG. 6.

The evenly spaced broken lines shown in the drawings depict portions of the warehouse robot that form no part of the claimed design. The line-dot-line broken lines that encircle portions of FIGS. 1-6 and that border the FIGS. 9-26 detail views indicate outer limits of enlarged areas of the figures and form no part of the claimed design.

1 Claim, 26 Drawing Sheets
